[57] CLAIM

The ornamental design for a tub for bathing, as shown and described.

DESCRIPTION

FIG. 1 is a top plan view of a tub for bathing embodying my new design;

FIG. 2 is a perspective view taken from the top, front and left side thereof;

FIG. 3 is a cross-sectional view taken on line 3—3 of FIG. 1.

FIG. 4 is a cross-sectional view taken on line 4—4 of FIG. 1;

FIG. 5 is a top plan view of a second embodiment which is the mirror image of the embodiment of FIG. 1;

FIG. 6 is a top plan view of a third embodiment;

FIG. 7 is a perspective view taken from the top, front and left side of the embodiment of FIG. 6;

FIG. 8 is a cross-sectional view taken on line 8—8 of FIG. 6;

FIG. 9 is a cross-sectional view taken on line 9—9 of FIG. 6;

FIG. 10 is a cross-sectional view taken on line 10—10 of FIG. 6;

FIG. 11 is a top plan view of a fourth embodiment which is the mirror image of the embodiment of FIG. 6; and,

FIG. 12 is a typical cross-sectional view of the edge of each of the embodiments, taken along line 12—12 of FIG. 6.

The fragmentary broken line representations of a bathroom deck in FIGS. 2 and 7 and of mounting regions in FIGS. 2, 3, 6, 7, 8, and 11 are for the purpose of illustration only and form no part of the claimed design.
